MARINE DISTRESS SIGNALLING UNIT

Edwin B. Block, Playa Del Rey, Calif.

Application January 13, 1958, Serial No. 49,232

Term of patent 14 years

(Cl. D72—1)

Figure 1 is a perspective view of the marine distress signalling unit, embodying my new design, with a portion of the antenna element broken away for convenience of illustration.

Figure 2 is a bottom plan view.

I claim:

The ornamental design for a marine distress signalling unit, as shown.
